UNITED STATES PATENT OFFICE.

ARTHUR ILLINGWORTH GRABHAM, OF WELLINGTON, NEW ZEALAND.

RHEOSTAT.

1,098,718.

Specification of Letters Patent. Patented June 2, 1914.

Application filed November 8, 1912. Serial No. 730,210. 252-490

To all whom it may concern:

Be it known that I, ARTHUR ILLINGWORTH GRABHAM, subject of the King of Great Britain and Ireland, and residing at 5 30 Tinakori road, in the city of Wellington, in the Dominion of New Zealand, have invented a new and useful Improvement in Rheostats; and I do hereby declare the following to be a full, clear, and exact description of the same.

This invention relates to resistance compositions for employment in apparatus whereby the amount of current flowing to electrical lighting, heating or power devices 15 may be regulated and controlled.

The object of the invention is to produce a solid medium or resistance through which the current has to pass in order to give a resistance to the voltage and amperage varying directly according to the distance 20 through which the current passes.

By means of the invention the current of electricity may be gradually reduced from the maximum to a minimum or increased 25 from a minimum to a maximum either by steps or by sliding contact as may be desired.

The rheostat with which the composition is employed may be of any suitable kind according as to whether the medium is used 30 for controlling lighting, heating or power purposes.

A suitable rheostat for controlling current for electric lighting is shown in the 35 drawing in order to illustrate the use of the composition, and Figure 1 of which is a sectional elevation; Fig. 2 is a sectional plan, and Fig. 3 is a plan view of the rheostat.

The ingredients of which the block is 40 composed comprise generally manganese oxid, zinc oxid, silicate of soda, and brass filings in suitable proportions the whole being mixed together and molded into blocks or rods or into other suitable forms according to the shape that is required and if desired baked so as to obtain the required 45 hardness. I have found the following proportions suitable for a switch for a 100 volt circuit: manganese oxid, two drams, zinc oxid, two drams, silicate of soda of the viscous kind, one hundred minims, and brass filings from two and three quarters to three and one half drams.

50 Manganese oxid 2 drams.
Zinc oxid 2 drams.

Silicate of soda (of the viscous kind)
100 minims.
Brass filings 2 $\frac{1}{4}$ to 3 $\frac{1}{2}$ drams.

The viscous silicate of soda forms the 60 binding agent but if the solid silicate of soda is used a slight quantity of water must be added.

In the rheostat shown in the drawings a block 1 of semicircular or circular form is 65 employed having a contacting way 2 of desired shape formed throughout its upper surface. Along this contacting way a contacting piece 3 is adapted to contact and may comprise a roller pivoted in a bracket 70 4 fixed upon a sleeve 5 journaled upon a spindle 6 fixed in the base 7. The sleeve 5 passes through a covering casing 8 which may be screwed or otherwise fixed to the base 7 while a coil spring 9 located upon the sleeve 6 in compression between the bracket 4 and the covering casing 8 gives the required tension to the contact piece 3 upon the contacting way 2. One lead wire 10 of the circuit is connected to a binding 80 post 11 fixed in the base 7 while one end of the block 1 is provided with a metal portion 12 which also passes into the post and is retained by the screw 13 in order to make a good electrical connection with the block 1. 85 The wire 14 which leads to the electrical device is connected to a binding post 15 also fixed in the base 7 and secured by nuts 16. A wire 17 makes electrical connection with the binding post 15 and the spindle 6. 90

The block 1 is mounted upon an asbestos slate plate 18 fixed upon the spindle 6 by nuts 19 and spaced a suitable distance from the base 7 in order to prevent undue heating 95 of the base.

A handle 20 is fixed upon the sleeve 5 for operating the contacting piece 3. In Fig. 3 the handle portion 20 is fixed to the bracket 4 while the slot 21 is provided for the handle to travel in. A stop 22 at one end of the block limits the movement of the contacting piece 3 in that direction, this stop is not in contact with the block 1 so that when the contacting piece 3 is resting upon it no current will flow through the block. 100

When it is desired to obtain the varying degrees of light, heat or power as the case may be, the handle 20 is operated so as to cause the roller 3 to contact with a different part of the block, and when the contact 3 110 is in contact with the stop 22 at the end of

- the block remote from the binding post 11 the current is then cut off and when it is in contact with the metal binding post 11 at the other end of the block the full glow of 5 the current will pass through the circuit. When the contact 3 is in contact with the end of the block remote from the binding post 11 the minimum amount of current will flow to the electrical device as the case may 10 be. By adjusting the contacting piece to different positions between the minimum and the maximum the desired amount of current is caused to pass to the electrical device.
- 15 I claim:
1. In a rheostat a resistance block consist-

ing of manganese oxid, zinc oxid, silicate of soda, and brass filings mixed together in suitable proportions.

2. In a rheostat a resistance block consisting of manganese oxid two (2) drams, zinc oxid (two) 2 drams, silicate of soda, one hundred (100) minims and brass filings, two and three-quarters (2 $\frac{3}{4}$) to three and one-half (3 $\frac{1}{2}$) drams. 20 25

In testimony whereof, I have signed my name to this specification in the presence of two subscribing witnesses.

ARTHUR ILLINGWORTH GRAHAM.
